SCARF

Elias Buchman, Chicago, Ill., assignor to American Feather Products Corporation, Chicago, Ill., a corporation of Illinois

Application February 24, 1936, Serial No. 65,194

1 Claim. (Cl. 2—91)

This invention relates to articles of apparel such as are known as mufflers or scarfs.

It is one of the objects of the present invention to provide a muffler or scarf which is exceedingly warm, yet light in weight, comparatively thin, and soft and flexible. It is a further object of the present invention to provide a scarf of the above character which will retain its shape even after prolonged usage. It is a still further object of the present invention to provide a scarf of the above character which shall be simple and economical of construction and which can be made to be very attractive to the eye without increasing the cost thereof.

I am aware that it has been proposed to provide scarfs with linings to increase their warmth. Scarfs with linings are subject to certain disadvantages which, in many instances, exceed the advantage of increased warmth. After washing or cleaning it is difficult to iron such a scarf properly, hence such scarfs frequently have objectionable folds or wrinkles. Furthermore, unequal shrinking of the lining and the outer cloth is frequently responsible for loss of shape of the scarf.

In addition to the above objections, the lining generally imparts an undesirable stiffness to the scarf.

It is an object of the present invention to provide a scarf as warm as, if not warmer than, a lined scarf, and yet not subject to the disadvantages inherent in lined scarfs, as set forth above. I have discovered that a light filling of feathery down, within the scarf, accomplishes all of the results above set forth, without introducing the disadvantages that are inherent in a lined scarf. By suitable stitching, the interior of the scarf may be subdivided into a plurality of separate small sections, thus preventing the accumulation of the down at any one place in the scarf. If desired, the stitching may be utilized also for forming an ornamental design on the scarf.

I have found that down possesses a desirable characteristic of resiliency not possessed by other shredded heat insulating substances. It remains soft even after prolonged usage of the scarf, and tends to maintain a sufficient light spreading between the opposite sides of the fabric of the scarf to render the same quite fluffy, which produces a very pleasant feeling, when used.

The attainment of the above and further objects of the present invention will be apparent from the following specification taken in conjunction with the accompanying drawing forming a part thereof.

In the drawing:

Figure 1 is a perspective view illustrating my improved scarf in normal use;

Figure 2 is a sectional view taken on the line 2—2 of Figure 1 and illustrating the stitching; 5

Figure 3 is a diagrammatic view illustrating a modified construction; and

Figure 4 is a fragmentary sectional view of one of the edges of the scarf of Figure 3.

Reference may now be had more particularly to the scarf shown in Figures 1 and 2. The scarf consists of a body of fabric folded upon itself to form a long, and comparatively narrow, envelope and suitably stitched together. The top of the envelope is illustrated at 1 and the bottom at 2. 15 The two longitudinally extending ends are suitably stitched together, on the interior of the envelope, as illustrated at 3. The material used may be any closely woven cotton or silk fabric, or any other closely woven cloth material. The 20 purpose of the close weaving is to render the cloth proof against the penetration of fine feathery down therethrough. There are numerous cloths on the market suitable for this purpose, such as the cloths which are used on bedding, quilts, or 25 the like, that contain down. One suitable cloth is known by the trade name "Cellenese taffeta" cloth. Another suitable cloth is known by the trade name "Celine satteeen". Any cloth suitable for the purpose may be used.

The envelope is filled with a loose filling of fine, feathery down 3. The amount of down used is rather small, so that the envelope is not distended an appreciable amount. For instance, in the muffler, or scarf, shown in Figure 1, which 35 is of a substantially rectangular shape, approximately 55 inches long and 6 inches wide, one ounce of down was sufficient. It is to be understood, however, that the present invention is not limited to these precise dimensions, or to this 40 precise amount of down. After the down has been placed in the envelope the fabric is suitably stitched to close the ends thereof. Thereafter, the down is uniformly distributed throughout the body of the envelope and the two opposite cloth surfaces 1 and 2 are stitched together by a series of fine close stitches, indicated at 4. This divides the interior of the scarf into a plurality of sections, such as indicated at 5, 6, and 7, each section being closed off from the adjacent 50 sections so that substantially no down can travel from one section to an adjacent section. By this arrangement I preclude the possibility of large accumulations of down in any one place within the scarf.

The down has the desired heat insulating properties so that the muffler, or scarf, has the desired characteristic of being warm. The one ounce, or so, of down does not appreciably increase the weight of the scarf. I have found, also, that the down remains soft and fluffy even after a long usage of the scarf. Furthermore, the down has a very desirable characteristic of elasticity and tends to keep the surfaces 1 and 10 2 of the fabric sufficiently spread apart, thereby assuring a distribution of the down, and at the same time render the scarf soft and agreeable to the touch. Also, the scarf does not tend to lose its shape after long usage and repeated cleanings thereof.

I have shown the stitching 4, which subdivides the scarf into a plurality of sections, in the form of a number of triangles. It is, however, to be understood that this is merely illustrative, as 20 any other shape can be used. Furthermore, the stitching 4, which serves the useful purpose previously set forth, may also be utilized for ornamental purposes, and may be arranged to form any desired pleasing pattern on the scarf.

25 The scarf of Figures 3 and 4 is of a construction such as described above in connection with Figures 1 and 2 and, in addition, is provided with what is known as a "zipper" 18, for closing the front of the scarf. The "zipper" comprises a 30 piece of strong fabric 11 in each of the two adjoining edges of the scarf, which pieces are provided with suitable metallic interlocking projections that may be brought into or out of inter-

locking relationship by means of the usual slideable locking member 12. The "zipper" construction is of the type now in common use on garments and which permits a complete separation of the two parts that are to be joined together, so that the scarf can be placed around the neck of a wearer without having to pass the same over the head. That is, when the locking member is moved downwardly to its unlocking position, the two lower ends 13 and 14 of the scarf may 10 be completely separated.

In compliance with the requirements of the patent statutes I have here shown and described a few preferred embodiments of my invention. It is, however, to be understood that the invention is not limited to the precise constructions here shown, the same being merely illustrative of the principles of the invention. What I consider new, and desire to secure by Letters Patent, is:

A scarf comprising fabric stitched to form a 20 comparatively long and narrow envelope of a length and width sufficient to permit the same to be looped around the neck of a person and worn as a chest protector, said scarf fabric being comparatively closely woven to render the same 25 substantially proof against the penetration of down therethrough, a light, loose, filling of down in the envelope, and stitching extending through the envelope and dividing the same into a plurality of sections for inhibiting movement of 30 down from one part of the scarf to a distant part thereof.

ELIAS BUCHMAN.
